E. Marsh,

Derrick.

Patented Feb. 12, 1836.

Feb. 12. 1836 9389X
Elias Marsh, Oswego New York.

Letters Patent.

The schedule referred to in these Letters Patent, and making part of the same, containing a description in the words of the said Elias Marsh, himself of his improvement in the crane for elevating and removing heavy bodies.

To all to whom these presents shall come; Be it known that I, Elias Marsh of the town of Oswego in the County of Oswego and State of New York, have invented a new and useful improvement in the crane for removing & elevating heavy bodies, and for other purposes, and that the following is a full and exact description of the construction and operation of the said crane as invented or improved by me. The principal parts of the Machine are the frame, the boom and arm, the drum, the shaft and the load. First the frame (see fig 1 a perspective drawing of the machine) is constructed of three substantial sill pieces, tenoned together in form of a triangle A. B. C. which I prefer making rectangular at A. The angle at which the arm is to be placed, from each angle rises a strong upright timber tenoned into the sill pieces and receiving at their upper ends the side shafts &. and cap pieces &. Braces & are also added for the purpose of stiffening the frame, and a strong brace or cross piece D extends from the top of the upright at the right angle (which for distinction I shall call the king post) to the middle of the cap piece C. 2nd.

The arm and boom the first A. B. is made of a single piece of timber, of dimensions proportioned to the work for which the crane is to be employed, with one or more pulleys &c. at the outer extremity & to receive the hoisting rope which passes to the block C and a double leading pulley & at the inner extremity

8 by which the hoisting rope(s) from the drum is always kept on the arm and the force thus made to act in the direction of its length and of the brace P. a hole is also bored on the outer side of the end of which receives a strong iron gudgeon made fast in the top of the king post upon which the arm traverses as a centre of motion; the Boom B. descends obliquely to the foot of the king post against which it bears, being kept in place simply by a semicircular notch cut out of the solid or formed by wooden jaws bolted on the sides of the boom, the foot of the post being also rounded so as to allow the boom to traverse freely and without much friction also for the same purpose a projecting collar of iron or hard wood is placed at the foot of the post which receives the downward bearing of the boom. For strengthening the boom as well as for convenience in handling the crane when unshifted it is connected near the middle joint with the inner end of the arm by a strong bar, of iron or wood 3 in. The Drum D is made of a solid cylinder of hard wood of suitable dimensions, it is pierced through the centre its whole length to receive the iron gudgeon & of the shaft P, on the lower end is bolted a disk of iron indented as hereinafter mentioned (l see fig 3) having a hole h for the passage of the gudgeon, it also projects a short distance beyond the cylinder forming a flange to keep up the rope. The top is covered with a circular iron plate, having at the centre a staple & a pivot pin which latter is fastened to a small lever I secured to the top of the frame above the drum by which the latter can be raised or lowered and the coupling with the shaft be thrown out, or into gear at pleasure. From the shaft P is of wood having a strong iron gudgeon & in the upper end, which which passes into the drum the whole length of the latter and forms a shaft

or spindle upon which the drum turns loosely, upon the top of the shaft is secured a disk or coupling-wheel to the teeth or knobs of which 4.1.1. match the sinks 3.2.2. of the disk on the drum, the upper end of the shaft is confined against the cap piece & by a suitable box and screw bolts & the lower end has a short quiggin which is stepped into the centre of a solid horizontal catch wheel T secured to the middle of that side under the cap piece G, a pale H, is attached to the foot of the shaft which takes in the catch T and prevents the shaft from moving back. A strong lever Q is mortised into the shaft to which the moving power is applied, ^{operation} the machine being placed in a suitable position the body to be raised is attached to the hook of the block O, and the shaft p, feet in revolution either by horse, hand or other power when the weight is raised to the desired height the arm is turned to the required position and the drum being raised by the lever I, the body is suddenly deposited without the delay & trouble of stopping the shaft and removing during the whole operation the force being made by the peculiar construction of the machine, to act very evenly in the direction of the length of the arm and of the brace P, it will operate equally well in any position of the arm. When the machine is to be used in taking up all canal locks or similar work, the arm and boom are each to have a groove for the passage of the rope, and a pulley or pulleys moveable along the top of the arm are to be used in lieu of the fixed pulleys &c. -

Now what I claim as my invention is the coupling of the drum and the peculiar arrangement by which the arm is left free to move without the force is operating, or by which the force applied is made to act & react in the direction of the arm and connecting brace, in any position of the arm, without the interposition of sheath ropes, wire glasses &c. attached to the

216.

9389X

broom as in ordinary use. In testimony that the foregoing is a true specification of my said improvement I have hereunto set my hand this 9th day of January 1836
